UNITED STATES PATENT OFFICE.

JAMES A. TILDEN, OF HYDE PARK, MASSACHUSETTS.

VALVE.

No. 853,274.

Specification of Letters Patent.

Patented May 14, 1907.

Application filed December 6, 1905. Serial No. 290,647.

To all whom it may concern:

Be it known that I, JAMES A. TILDEN, a citizen of the United States, residing in Hyde Park, in the county of Norfolk and State of Massachusetts, have invented certain new and useful Improvements in Valves, of which the following is a specification.

My invention relates to valves and particularly to those operable by fluid pressure. 10 Its object is to generally improve the construction of such devices.

In the accompanying drawings, Figure 1 is a top plan view of one embodiment of my invention, the cap being removed; Fig. 2 is a 15 full vertical, longitudinal section on the line 2-2 of Fig. 1, and Figs. 3 and 4 are enlarged sectional details on the lines 3-3 and 4-4, respectively, of Fig. 2.

Similar characters indicate like parts 20 throughout the several figures of the drawings.

A casing 10 of any convenient form is provided with main flow openings 11 and 12, and with a hand opening 13 which may be 25 closed by a hollow dome-shaped cap or cover 14. One of the flow openings is adapted to receive a separable sleeve 15, having at its inner end an annular enlargement 16 for contact with a face 17 upon the casing, this serving to position the sleeve. Surrounding the inner end of the sleeve-opening is an annular surface 18 furnishing a seat about which extends a preferably continuous depression 19. Through the enlargement, 16, conveniently 30 at opposite sides, are passages 20 communicating with the depression. These passages are threaded and have portions situated in alignment with openings 21 through the casing. Extending through the openings 21 35 into the passages 20 are tubular members 22-22 threaded to engage the seat portion. The outer end of each of these tubular members is provided with a head 23 by which it may be turned, and each member may be 40 locked in position by a nut 24 operating upon its threaded exterior and co-acting with a packing-ring 24^a situated between it and the casing. The outer ends of the tubes have internal threads at 25^b to permit the connection of suitable pipes. It will be seen that 45 the tubular members not only furnish passages connecting the seat depression with the atmosphere or some point outside the casing, but also secure the seat-sleeve in place. Extending from one side of the seat is a 50 projection 25, there being two of these here

illustrated situated side by side at the upper portion of the enlargement 16 below the cap. These projections or lugs are bored to receive a pivot-pin 26 about which may swing an 60 arm 27. This arm carries the movable or gate portion of the valve, which is shown as in the form of a disk 28 co-operating with the seat. The disk may be secured between a plate 29 screwed upon a bolt 30 passing 65 through an opening in the arm and having its head upon the opposite side, and a plate 31 surrounding the bolt and locked by nuts 32. The plate 29 is so positioned upon the bolt that it is somewhat loose in its relation to the 70 arm, the resulting play of the disk and its securing elements allowing it to adjust itself with respect to the seat to secure proper co-operation. To insure the seating of the gate, the arm is provided with a weight, 75 which is illustrated as in the form of a hollow sphere 34 serving as a receptacle to which access may be had through an opening normally closed by a plug 35.

The construction above described renders 80 it possible to assemble and to true the seat and body outside the casing, and therefore with every part freely under the eye of the workman. As the dimensions of these connected elements are too great with relation to 85 the containing chamber in the casing to allow them to be put in place together, the sleeve may be first inserted and locked by the tubular members. Then the arm of the gate is introduced between the projections 25 with 90 the pivot openings opposite one another and the pin inserted through an aligned opening 36 in the casing, the length of said pin being such as to enable this to be done conveniently. The opening 36 is then closed by a 95 plug 37. One of the tubes 22 may be plugged while pipe connection is made with the other, thus allowing the valve to be made up in a system either right or left.

When the valve is in use in a system in 100 which a fluid acts against both faces the seat depression, being open to a point of less pressure than normally exists within the system, will give a differential pressure upon the gate which will be greatest at the side opposite the 105 depression. This acts to maintain a closure of the valve, but when the pressure in the system for any reason decreases upon the outer face of the gate to an extent greater than that exerted by the combined pressure-differential and the weight, the valve at once 110 opens. It should be noted that as the

weight swings upwardly into the cap, approaching a vertical through the pivot, its effect decreases and it therefore offers less resistance. While the valve is open a limited flow will occur through the seat-depression and the retaining connection, thus giving an indication of the change of condition. This flow may also be applied to any suitable use. When normal conditions are again established the weight promptly closes the valve, simultaneously shutting off the main flow and that through the differential-seat. To control the effect of the differential, the weight may be varied by placing shot or other small objects within the receptacle or removing those which have been previously supplied.

Having thus described my invention, I claim:

- 20 1. A valve comprising a casing, a separable seat portion provided with a passage opening into the casing, and a member extending through the casing into engagement with the seat portion and being adapted to retain it in place, said member having a passage communicating with that in the seat portion.
- 25 2. A valve comprising a casing, a separable portion provided with a seat-surface in which is an opening, and a tubular member extending through the casing into the separable portion and communicating with the opening in the seat-surface.
- 30 3. In a valve, the combination with a casing, of a separable sleeve therein provided with a seat-surface in which is a depression, said sleeve also having a passage leading from

the depression to the outside of the sleeve and being threaded at the latter point, and a tube extending through the casing and being threaded to coöperate with the sleeve-passage.

4. A valve comprising a casing, a separable seat portion provided with a depression, and means for retaining the seat portion within the casing, said retaining means being provided with a passage communicating with the depression.

5. A valve comprising a casing, a separable seat portion provided with a depression, a gate portion mounted to move upon the seat portion, and means for retaining the seat portion within the casing, said retaining means being provided with a passage communicating with the depression.

55 6. A valve comprising a casing having a differential seat portion, a gate portion co-operating with the seat and being provided with a chamber, said chamber having an opening, and a closure for the opening.

60 7. A valve comprising a casing provided with an opening, seat and gate portions separable from the casing, a pivot connecting the seat and gate and terminating within the casing in alinement with its opening, and a removable closure for the opening.

Signed at Boston, in the county of Suffolk and State of Massachusetts, this 29th day of November, 1905.

JAMES A. TILDEN.
